UNITED STATES PATENT OFFICE.

JOHN J. W. KENAN AND WILLIAM M. CADY, OF NEWARK, NEW JERSEY.

RADIO APPARATUS.

Application filed March 28, 1925. Serial No. 19,023.

This invention relates in general to radio apparatus which includes relatively movable parts and more particularly to variable rotary plate electric condensers commonly used in radio receiving apparatus.

One object of the invention is to provide radio apparatus of the general character described embodying a novel and improved mounting of the fixed and the movable parts which is simple and inexpensive in construction and easy and reliable in operation.

Another object is to provide a novel and improved apparatus of the character described in which the parts are wholly enclosed in a casing and wherein the parts are so arranged that the necessary adjustments of the parts relatively to each other in operating the apparatus, are obtained by rotation of the casing, whereby the parts can be effectually protected from atmospheric conditions and at the same time simple and reliable operation ensured.

A further object is to provide radio apparatus of the character described having relatively movable parts arranged within a rotatable casing, certain of said parts being mounted pendulously upon the walls of said casing coaxially with the casing and the others of said parts being fixedly secured to the casing to move therewith relatively to the first-mentioned parts upon rotation of said casing.

Other objects are to provide a variable rotary plate electric condenser embodying a substantially cylindrical casing journaled to rotate on its axis and having one set of plates pendulously mounted within and coaxially with said casing and another set of plates mounted on the circumferential walls of said casing whereby rotation of said casing causes relative movement of said two sets of plates; to provide novel electromagnetic means for holding said pendulously mounted parts against oscillation, and to obtain other results and advantages as may be brought out by the following description.

Referring to the accompanying drawings in which corresponding and like parts are designated throughout the several views by the same reference characters,

Figure 1 is a front elevation of a variable electric condenser embodying the invention showing the same mounted in its relation to a panel of radio receiving set which is fragmentarily illustrated;

Figure 2 is a side elevation of the condenser;

Figure 3 is a longitudinal vertical sectional view, taken on the line 3-3 of Figure 2;

Figure 4 is a transverse vertical sectional view, taken on the line 4-4 of Figure 1;

Figure 5 is a composite fragmentary perspective sectional view showing the manner of assembling the two casing sections and the condenser plates.

Specifically describing the embodiment of the invention illustrated in Figures 1-5 inclusive, the condenser includes a substantially hollow cylindrical casing 35 which is preferably vacuous, that is, a complete or partial vacuum obtains within the casing. This casing is formed with coaxially exterior projecting hubs or trunnions 36, and at its ends on the interior is provided with two metallic coaxial bearing blocks 37 which support through conical bearings 38 a shaft 39. The bearing blocks 37 may be fixedly secured in recesses in the walls of the casing. A plurality of condenser plates 40 of the usual construction are clamped upon the shaft 39 in the usual manner. It will thus be observed that the plates 40 are pendulously mounted upon the walls of the casing and will swing by action of gravity upon the shaft 39 which is rotatable in the bearing blocks 37. These plates form in effect the stator plates for the condenser.

The circumferential walls of the casing 35 are formed exteriorly with a transverse dove-tail groove 41 in which is mounted a metallic shoe 42 and a metallic block 43 having transverse slots 44 in which are fitted lugs 45 projecting from the edges of rotor condenser plates 46. With this construction, it will be obvious that by rotating the casing 35 the relations of the two sets of condenser plates may be changed to vary the capacity of the condenser.

The casing 35 may be rotatably mounted in any suitable manner, but preferably we provide on one of the trunnions 36 a metallic ferrule 47 which is electrically connected to one of the burner blocks 37 by means of a wire 48 burned through the wall of the casing in any suitable manner, such as that used in connecting wires to X-ray tubes, and electrically connected to the block 37 and ferrule 47. The other trunnion 36 has secured thereto a socket member 49 which is formed with an integral spindle or stud

shaft 50. The ferrule 47 and the socket member 49 serve as the bearing bushings for journaling the trunnions 36 in bearing posts 51 which are fixedly secured to a base 52.

The rotor plates 46 are electrically connected to the socket member 49 by means of a wire burned through the wall of the casing 35 and electrically connected to said socket member and the shoe 42. Thus, the posts 51 are electrically connected to the respective rotor plates and stator plates 46 and 40, and the said posts may be electrically connected to corresponding binding posts 53 in any suitable manner as indicated at 54.

For rotating the stud shaft 50 and the casing 35 we may utilize an ordinary dial or knob 55. In the operation of the condenser, it will be understood that the action of gravity will tend to maintain the stator plates 40 in fixed position, and that rotation of the casing 35 will move the rotor plates 46 relatively to the stator plates. It may be necessary to provide means to prevent oscillation of the plates 40, particularly where the condenser is used at a point where constant vibrations are encountered. For this purpose we may utilize a block 56 of magnetic material such as steel, fixedly mounted on the end of an arm 57 secured to the shaft 39, and mount a permanent magnet or electromagnet 60 in one of the bearing posts 51 opposite said block 56. Magnetic attraction of the block 56 by the magnet 60 will hold the plates 40 substantially stationary under all conditions.

For assembling the parts of the apparatus within the casing 35, we preferably initially form the casing of two complementary sections 61. Each of the sections has formed therein a portion of the dove-tail groove 41 and the shoe 42 is formed in two pieces. The rotor plate supporting block 43 is formed in one piece and is initially slid into one of the sections of the shoe 42. The stator plates 40 having been arranged so as to mount the shaft 39 in the respective bearing blocks 38, the two sections 61 are brought together so that the portion of the shoe 42 carried by one section slides over the projecting end of the block 44 carried by the other section. The meeting edges of the casing sections 61 are then fused together in any suitable manner, after which the casing is evacuated according to known methods and with known apparatus.

From the above description, it will be understood that the invention enables the protection of radio apparatus from the effects of atmospheric conditions and accordingly losses commonly due to defective dielectric or leakage between the plates or conducting parts, frictional hysteresis, eddy currents, etc. are eliminated.

The vacuous condition within the casing

eliminates the gases of the atmosphere, so that all conducting paths which may be produced by the atmosphere are eliminated from the apparatus. Also, the intercapacities of the vacuum of the condenser will equalize and balance the intercapacities of the vacuum tubes used in radio receiving sets, thereby producing more perfect resonance. Furthermore, deterioration of the apparatus due to action of the elements is prevented.

While we have shown and described the invention embodied in an electric condenser it will be understood that the invention is susceptible of use in connection with any type of radio and electrical apparatus in which there are parts likely to be affected by atmospheric conditions, for instance, variometers, vario-couplers, etc. Therefore, we do not desire to be understood as limiting ourselves except as required by the following claims when construed in the light of the prior art.

Having thus described the invention, what we claim is:

1. Electrical apparatus comprising a rotatable electrical conducting element, a second electrical conducting element pendulously mounted coaxially with said rotatable member to cooperate therewith, means for rotating said first-mentioned conducting element relatively to the second-mentioned conducting element, and cooperating magnetic elements one mounted on a fixed support and the other mounted on the second-mentioned conducting element to hold said second-mentioned conducting element against oscillation.

2. Electrical apparatus comprising a vacuous rotatable casing, an electrical conducting element fixedly mounted upon and within said casing, a second electrical conducting element pendulously mounted upon and within said casing coaxially therewith, means for rotating said casing, and cooperating magnetic elements one on the second-mentioned conducting element and the other fixedly mounted exteriorly of said casing for holding said second-mentioned conducting element against oscillation.

3. An electrical condenser comprising a rotatable casing including two cup-like sections having their edges secured together and formed with aligned grooves opening through said edges substantially parallel with the axis of rotation of said casing, a plurality of spaced and parallel conducting plates fixedly mounted within said grooves, a plurality of spaced and parallel conducting plates pendulously mounted within said casing co-axially therewith in alternate relation to the first-mentioned plates, means for rotating said casing, and terminals for said plates extending through said casing.

4. Electrical apparatus comprising a rotatable casing including two cup-like sections having their edges connected together and formed with aligned grooves opening 5 through said edges substantially parallel with the axis of rotation of said casing, a supporting block fitted in said grooves and having transverse grooves, a plurality of conducting plates one mounted edgewise in 10 each of said grooves, a plurality of spaced and parallel conducting plates pendulously mounted within said casing co-axially therewith in alternate relation to the first-mentioned plates, means for rotating said casing, 15 and terminals for said plates extending through said casing.

5. An electrical condenser comprising a

vacuous rotatable casing including two cup-like sections of fusible material having their edges fused together and formed with aligned 20 grooves opening through said edges substantially parallel with the axis of rotation of said casing, a plurality of spaced and parallel conducting plates fixedly mounted within 25 said grooves, a plurality of spaced and parallel conducting plates pendulously mounted within said casing co-axially therewith in alternate relation to the first-mentioned plates, means for rotating said casing, and terminals for said plates extending 30 through said casing.
